UNITED STATES PATENT OFFICE.

LOUIS F. GROSS, OF SCRANTON, PENNSYLVANIA.

DENTAL-DISK HOLDER.

1,190,152.

Specification of Letters Patent.

Patented July 4, 1916.

Application filed March 9, 1915. Serial No. 13,295.

To all whom it may concern:

Be it known that I, Louis F. Gross, a citizen of the United States, residing at Scranton, in the county of Lackawanna and 5 State of Pennsylvania, have invented new and useful Improvements in a Dental-Disk Holder, of which the following is a specification.

My invention relates to a new form of 10 dental disk holder, in which a multiple number of disks of varying sizes and kinds may be mounted on a multiple number of posts, either spring or rigid, as desired, fastened to or mounted on a supporting plate 15 and arbor which is sustained and may be revolved on a vertical shaft supported by a substantial base; and the objects of my invention are; first, to provide a universal and compact holder for storing and retaining a 20 multiple number and kind of disks; second, a convenient holder which may be placed and adjusted to the will and convenience of the operator; third, to lock the disk in place at the will of the operator, as in case of accidental upsetting or other inconvenience, 25 that they may not be displaced. I attain these objects by the mechanism illustrated in the accompanying drawings, in which,—

Figure 1, is a general perspective view of 30 machine, showing one post (4) disengaged so as to remove disks; Fig. 2, is a vertical sectional view showing detail construction of the same.

Similar letters refer to similar parts 35 throughout the several views.

1 is a supporting base to which is fastened a vertical shaft 2. This base and shaft may be in one or in separate pieces.

3 is a cylindrical block of wood, fiber, or 40 other desirable material, with vertical grooves 4 on the outside surface, made to fit and receive spring loops which receive and store disks 5, as seen in Fig. 1. A wide bottom plate 6 is secured by screws 10 to the 45 lower end of the core and is provided with radial slots 7 around its periphery, and a top plate 8 is secured by screws 9 to the upper end of the core and overlies the upper ends of its grooves 4 slightly. Said 50 loops are preferably made of spring material held in place in grooves on outside surface of and to core 3 by cylinder 11 which surrounds and is slightly shorter than the core. Thus the shank of each loop is held 55 removably in place between the two plates 6 and 8, its lower end is bent outward as at

12 over the exposed part of the lower plate 6, carried downward in a slot 7 therein as seen at 13, and then carried upward through such slot in a spring tongue 14; whereas the 60 upper end of said shank is bent outward as at 12' into an arm 15 which has a hook 16 at its outer extremity adapted to engage said tongue. The normal position of the latter is about that shown at the left of Fig. 65 1, or in other words when disengaged from the hook it springs outward so that the disks 5 or other articles stored thereon may be lifted off the tongue with ease; but at other times the tongue is borne inward and engaged with the hook 16 as seen in Fig. 2 so 70 that whatever is mounted on the tongue may not be dislodged therefrom, even if the entire device should be accidentally knocked over. The depressed portion 13 of each 75 loop serves two functions. First it gives resiliency to the loop between its tongue 14 and the remaining portion thereof, so that the tongue itself really does not have to bend much if any, and yet this resiliency is 80 below the line of the bottom plate 6 so that it does not detract from the length of the tongue and the capability thereof for storage. Second the engagement of the de- 85 pressed portion 13 with the slot 7 prevents 90 the swinging of the loop from side to side which otherwise might occur because its upright shank is mounted in one of the grooves 4. It will be obvious that in order to serve these two functions it is not es- 95 sential that the depressed portion 13 be given exactly the configuration shown in the draw- 100 ings, so long as it is a bend or perhaps even a coil of the wire of which the loop is com- 105 posed, and it projects through the slot 7 and stands mainly beneath the line of the plate 6. At 8' shaft 2 is reduced in size from the main body so as to form a shoulder to support plate 8 and allow the holder or container to revolve thereon. This shoulder 100 may be on the lower end so as to support plate 6 as desired or at any other desired point or by any known convenient method; 17 is a nut threaded and screwed to the upper end of shaft 2 to hold or lock the holder 105 or container in place.

Having thus described the invention, what is claimed is:

1. In a device of the class described, the combination with a core supported on an 110 upright axis, and a plate secured across its lower end and projecting beyond its face

and provided with radial slots in its periphery; of a series of loops whereof each has an upright shank secured to said core, an outwardly projecting arm at the upper end 5 of the shank provided with a hook at its extremity, the lower end of the shank being bent outward over said plate and then depressed through one of said slots, and a tongue rising from the depressed portion 10 and removably engaged with said hook.

2. In a device of the class described, the combination with an upright support, a core rotatably mounted thereon and having upright grooves in its surface, and a plate 15 secured to the lower end of the core and projecting beyond said surface, the plate having radial openings in its projecting portion; of a series of loops whereof each has a straight upright shank mounted in one of 20 said grooves, an outturned and hooked arm at its upper end, and its lower end bent outward over the plate, depressed into one of said openings therein, and then brought up-

ward again in said opening into a spring tongue removably engaging said hook. 25

3. In a device of the character described, the combination with a cylindrical core mounted on an upright axis and having upright grooves in its surface, plates secured to its upper and lower ends and overlying the extremities of said grooves, one of the plates having openings alined with the grooves, and a cylinder surrounding said core and its grooves and shorter than the core so that the ends of the grooves adjacent the plates are left open; of a series 30 of loops whereof each has a shank lying in one groove, ends bent over the edges of the surrounding cylinder and one of them engaging one of said openings, and a hook on 35 one end and a spring tongue on the other, for the purpose set forth. 40
